(57) **CLAIM**

We claim the ornamental design for a neck strap for a respirator, as shown and described.

DESCRIPTION

FIG. 1 is a top, right, front perspective view of a neck strap for a respirator, shown in a first configuration;

FIG. 2 is a top, left, rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a top, left, rear perspective view, shown in a second configuration for clarity of disclosure.

1 Claim, 5 Drawing Sheets
